UNITED STATES PATENT OFFICE.

FERDINANDO G. SALERNO, OF CHICAGO, ILLINOIS.

DETACHABLE BOX COVER.

Application filed June 30, 1922. Serial No. 572,011.

To all whom it may concern:

Be it known that I, FERDINANDO G. SALERNO, a citizen of the United States, residing at Chicago, in the county of Cook and State of Illinois, have invented certain new and useful Improvements in Detachable Box Covers, of which the following is a specification.

My invention relates to a novel hinged cover or door which has been designed with especial reference to its use as a closure for boxes in which biscuits, wafers and like goods manufactured by wholesale manufacturing bakers are packed and distributed to the retail trade. The object of my invention is the production of an inexpensive and practical cover which can be supplied to retail dealers and by them readily applied to such a box after the original cover of nailed boards has been removed, and used to give ready access to the box while the contents are being sold, and which, after the box has been emptied, can be readily removed and placed on a fresh box. To this end I have devised novel hinge members secured to the cover and having one element adapted to be detachably affixed to a box side of standard construction, and my invention relates to the construction and arrangement of these hinge members and their combination and association with the cover and the box to attain the objects and effect the results of such an organization for realizing the advantages before referred to. In the appended claims I have more particularly pointed out the essential elements of my invention and distinguished it from the prior art known to me, it being understood, however, that the particular construction hereinafter described and which is shown in the drawings is susceptible of modification and variation within the true scope and intendment of the claims and without departing from the spirit of my invention.

In the drawings I have illustrated an embodiment of my invention in a preferred form, Figure 1 illustrating a portion of a box with my novel hinged cover applied thereto; Fig. 2 a sectional view; Fig. 3 a perspective view of the hinge member.

The same reference characters indicate the same parts in all the figures of the drawing.

The box 1 which is shown in part in Figure 1 of the drawing may be taken to be a box which has been received filled with wafers or other articles to be retailed and

from which the original covering of boards upon one side has been removed to permit the application of the cover 2 to the box side 1^a as a closure for the open side of the box. This cover consists of a glazed rectangular frame and is permanently equipped with a pair of hinges consisting each of a staple-like member, marked A as a whole, formed of heavy wire and having parallel prongs with portions 3 driven into the inner vertical member of the frame and intermediate portions 3 and a cross portion 3^a bent at right angles to the portions 3, so that such parts lie adjacent and parallel with the rear face of the frame member.

The cross member of the portion 4 is pivotally engaged by a substantially cylindrical bearing roll 5 formed in the intermediate portion of the other hinge member, marked B, which consists of a flat strip of stiff sheet metal having an inner end portion 6 arranged to cooperate with the inner face of the side of the box, a connecting cross-portion 7, the roll 5 before mentioned, an intermediate outer portion 8 parallel with the portion 6 and arranged to contact the outer face of the side of the box an obliquely-bent intermediate bracing portion 9, and a terminal cross-portion 10 in the plane of the cross portion 7 and abutting against the roll 5. It will be noted that when the cover is in wide open position the cross portion 10 serves as a stop which the face at the edge of the inner frame member of the cover may bring up against. The oblique portion 9 braces and stiffens the parts of the hinge member adjacent the bearing roll.

Near the outer end of the portion 6 of the hinge member B the metal is punched to form a short inwardly-extending engaging stud 11 which is sufficiently sharp to permit it to be forced into the box side 1^a after the hinge member has been sprung into engaging position. The inherent strength and resiliency of the metal, it will be understood are such that the hinges may readily be seated by the application of positive force, but will resist disengagement sufficiently to hold the box cover securely in position.

The roll of the hinge member B lies outside of the plane of the box side, and the pintle lies adjacent and slightly inside the plane of the inner face of the cover, so that when the door is swung to open position through an angle of 90°, the face of the

2. *Leucanthemum vulgare* L.

inner or hinged edge of the cover will bring up against the terminal stop portion 10 of the sheet metal hinge member, the cover standing clear, wholly outside the plane of the inner face of the side of the box.

As will be clear from the foregoing description, no nails, bolts or screws are needed for attachment of the cover to the box, and the cover can be more readily taken off one box and placed on another than in any prior removable cover of which I am aware. Moreover, such prior covers, so far as I am aware, have always consisted of hinged sections one of which was secured to the box, partially closing the side to which it was applied, whereas with my novel cover, the entire inside of the box is exposed when the cover is open.

20 While I have described my novel hinged cover with reference to the particular use for which it was devised, it will be understood that it is capable of being employed as a closure for any kind of container or receptacle, or for hingedly connecting any 25 kind of a leaf removably to a flat member correspondingly related to the leaf in the same relation that the cover herein described bears to the box side engaged by the hinges.

I claim:

30 1. A closure for open-side boxes and the
like comprising a cover equipped with hinges
having a pintle hinge element secured to
the cover and the other element formed of a
35 strip of sheet metal having parallel engag-
ing sides and a roll arranged to pivotally en-
gage said pintle.

2. A closure according to claim 1 in which said sheet metal hinge element is formed with a connecting cross portion intermediate 40 said roll and a terminal portion forming one of the parallel engaging sides.

3. A closure according to claim 1 in which said sheet metal hinge element is formed

with an oblique bracing portion connected to the outer one of said parallel sides and receiving support from said roll.

4. A closure according to claim 1 in which said sheet metal hinge element is formed with a stop arranged to cooperate with the face at the inner edge of the cover. 50

5. A closure according to claim 1 in which said sheet metal hinge element is formed with an oblique bracing portion connected to the outer one of said parallel sides and with a terminal cross portion forming a stop arranged to cooperate with the face at the inner edge of the cover. 55

6. A closure according to claim 1 in which said sheet metal hinge element is formed with an oblique bracing portion connected to the outer one of said parallel sides and also connected with a cross portion arranged at right angles with the parallel engaging sides and forming a stop arranged to co-operate with the face at the inner edge of the cover. 60 65

7. A closure according to claim 1 in which the axis of the hinge lies outside the plane of the outer face of the box side and adjacent the plane of the inner face of the cover. 70

8. A closure for open-side boxes and the like comprising a cover equipped with hinges having spring clip members arranged to detachably grip a box side, at least one such member being equipped with an engaging stud. 75

9. A closure for open-side boxes and the like comprising a cover equipped with hinges having a pintle member formed of wire having parallel prongs and a cross-portion 80 forming the pintle, said prongs being similarly bent to form end portions adapted to be driven edgewise into the cover and bring the axis of the pintle adjacent the plane of the inner face of the cover.

FERDINANDO G. SALERNO.
